UNITED STATES PATENT OFFICE.

CHARLES WARREN LEONARD, OF RICHMOND, VIRGINIA.

GREASE-CUP.

No. 826,259.

Specification of Letters Patent.

Patented July 17, 1906.

Application filed March 22, 1906. Serial No. 307,451.

To all whom it may concern.

Be it known that I, CHARLES WARREN LEONARD, a citizen of the United States, residing at Richmond, in the county of Henrico and State of Virginia, have invented a new and useful Grease-Cup, of which the following is a specification.

This invention relates to grease-cups for use in supplying lubricant to the wrist-pin of the drive-wheels of locomotives, although the same is equally adapted for use upon any bearings of a like nature wherein the rotatable element moves at a high speed. In devices of this character such as heretofore employed it has been necessary for the operator to manually adjust the cup at predetermined intervals for the purpose of pressing the lubricant so as to force it upon the rotatable surface, this adjustment only being possible when the mechanism has been brought to a standstill.

The object of this invention is to provide a cup having a forcing-piston which is adapted to automatically press the lubricant out of the cup.

The invention consists of a detachable lubricant-container having a forcing-piston therein the stem of which constitutes a guide for a weight which is slidably mounted thereon and is adapted to be thrown upward by the jolting of the mechanism and upon falling by gravity will drive the piston against the lubricant and force a portion thereof out of its container and into the bearing.

35 The invention also consists of means for rendering this operation noiseless and for controlling the feed of the lubricant.

The invention also consists of certain other novel features of construction and combinations of parts, which will be hereinafter more fully described, and pointed out in the claims.

In the accompanying drawings is shown the preferred form of the invention.

In said drawings, Figure 1 is an elevation showing the position assumed by the grease-cup upon the pitman of a locomotive. Fig. 2 is an enlarged longitudinal section through the grease-cup; and Fig. 3 is a section through the cup on line $x-x$, Fig. 2.

50 Referring to the figures by numerals of reference, 1 is a collar such as ordinarily formed at the end of a pitman 2 and adapted to surround a wrist-pin 3. This collar has a tubular internally-threaded extension 4 thereon,

from which extends an outlet-passage 5, 55 which is preferably provided with a tubular lining 6, having a head 7, which bears upon the bottom of the tubular extension 4 and has a concaved seat 8 at its upper end. Screwed into the extension 4 is the threaded 60 end 9 of a grease-receptacle 10, having an angular flange 11, adapted to bear upon the extension 4 when the receptacle is secured in position. The upper portion 12 of the receptacle 10 is of less diameter internally than the 65 lower portion 13, there being formed an interior angular shoulder 14 between the two portions 12 and 13. The large portion 13 of the receptacle is gradually tapered downward from the shoulder 14, so that the opening at 70 the lower end of the receptacle is of less diameter than the interior diameter of the receptacle at the base of the shoulder 14. This taper has been brought out in Fig. 2, wherein dotted lines are used to designate the position which would be assumed by the wall of 75 the receptacle if the same were not tapered.

Shoulder 14 constitutes an abutment for a follower or piston consisting of a head 15, having a rounded extension 16 upon its lower 80 face adapted to project into the socket 8, and an expandable metal ring 17 surrounds the head 15 and bears outwardly upon packing 18, which is adapted to be held upon the head by a washer 19, secured in place by 85 means of screws 20. By providing a resilient packing, such as herein described, the piston will contract in diameter as it moves from the shoulder 14 toward the lower end of the receptacle 10, and vice versa. A stem 21 extends from the head 15 through an opening 22, formed in the top of the receptacle 10, and loosely mounted on this stem is a substantially oval weight 23, which is free to slide upon the stem. A cushion 24, preferably 90 formed of rubber, is disposed upon the washer 19, and another cushion 25, of similar material, is located within the upper end of the receptacle 10.

In using the device herein described the 100 receptacle 10 is detached and inverted, so that the piston will assume a position against the shoulder 14. The lubricant, which is in the form of a cake, is inserted into the open end of the receptacle, so as to completely fill 105 the space between the piston and said end, and said receptacle is then replaced upon the extension 4. When the locomotive starts

forward, the movement of the parts will cause the weight 23 to be thrown violently upward and downward upon the rod 21, and as a result said weight will pound upon the piston 5 and drive it downward against the lubricant, forcing a portion thereof through the passage 5. As the lubricant is discharged in this manner the stroke of the weight will of course increase, and as the force of the blow exerted 10 thereby will correspondingly increase it is necessary to provide some means for correspondingly retaining the piston, so that the discharge of the lubricant will be maintained uniform. To produce this result, the lower portion of the receptacle 10 is contracted, as described, so as to cause the compression of ring 17 and packing 18, this compression being sufficient to offset the increased stroke of the weight. By utilizing 15 a cup such as herein described it becomes unnecessary for the engineer or other operator to give the same any attention, except when it is necessary to fill it, because the lubricant will be automatically discharged 20 whenever the engine is started or whenever 25 the weight is actuated upon the rod 21 through any jolting or irregular movement imparted to it.

What is claimed is—

- 30 1. The combination with a casing having an outlet; of means adapted to be reciprocated by sudden movement of the casing for forcing lubricant through the outlet, and means for resisting the movement of the first-mentioned means in proportion to the decrease of lubricant.
- 35 2. The combination with a casing for containing lubricant, said casing having an outlet; of a follower within the casing for bearing on the lubricant, and means adapted to be reciprocated by sudden movement of the casing for imparting movement to the follower, said casing adapted to gradually resist the movement of the follower.
- 40 45 3. The combination with a casing for containing lubricant, said casing having an outlet; of a follower movably mounted within the casing, and a weight loosely mounted above the follower, and adapted to be reciprocated by the sudden movement of the casing.
- 45 50 4. The combination with a casing for containing lubricant and having an outlet; of a follower mounted to slide within the casing; a rod extending from the piston, and a weight mounted to reciprocate upon the rod.
- 55 60 65 5. The combination with a casing for containing lubricant and having an outlet; of a follower mounted within the casing and adapted to bear upon the lubricant, a stem projecting from the follower, a weight loosely mounted upon the stem, and cushioning means within the path of the weight.
- 65 6. The combination with a casing for containing lubricant and having an outlet; of a

follower within the casing, a weight loosely mounted above and adapted to bear upon the follower, a guide for said weight, and cushioning means within the path of the weight.

70

7. The combination with a casing for containing lubricant and having an outlet; of a follower within the casing for bearing on the lubricant, means operated by the sudden movement of the casing for actuating the follower, and means for retarding the movement of said follower.

8. The combination with a casing for containing lubricant and having an outlet; of a follower within the casing adapted to bear upon the lubricant, a stem projecting from the follower, a weight loosely mounted on the stem and adapted to bear upon the follower, and means for retarding the movement of the follower in proportion to the increase of the movement of the weight.

80

9. The combination with a casing for containing lubricant and having an outlet; the interior of said casing being contracted toward the outlet; of a contractible follower mounted within the casing, a stem projecting therefrom, and an actuating - weight loosely mounted upon the stem.

85

10. The combination with a movable lubricant-receptacle having an outlet, the interior of said receptacle being contracted toward the outlet; of a contractible follower within the receptacle, a stem projecting therefrom, a weight loosely mounted on the stem for actuating the follower, and cushioning means within the path of the weight.

95

11. The combination with a movable bearing having an extension thereon; of a lubricant-containing casing detachably mounted within the extension and having an outlet, a follower mounted within the casing, a stem thereon, and a weight loosely mounted on the stem and adapted to be actuated by the movement of the casing.

105

12. The combination with a movable bearing having an extension thereon; of a lubricant-containing casing detachably mounted within the extension and having an outlet, the interior of said casing being contracted toward the outlet, a contractible follower mounted within the contracted portion of the receptacle and bearing against the wall thereof, a stem upon the follower, and a weight loosely mounted thereon and adapted to be actuated by the movement of the bearing.

110

13. The combination with a movable bearing having an extension thereon; of a lubricant-containing casing detachably mounted within the extension and having an outlet, the interior of said casing being contracted toward the outlet, a contractible follower mounted within the contracted portion of the receptacle and bearing against the wall thereof, a stem upon the follower, a weight 125

120

130

loosely mounted thereon and adapted to be actuated by the movement of the bearing, and cushions within the path of the weight.

14. The combination with a casing for containing lubricant, said casing provided with an outlet and having its interior contracted toward the outlet; of a head mounted within the receptacle, packing surrounding the head, resilient means interposed between the packing and head for holding said packing in contact with the wall of the contracted

portion, a stem projecting over the head, a weight loosely mounted thereon, and cushions in the path of the weight.

In testimony that I claim the foregoing as my own I have hereto affixed my signature in the presence of two witnesses.

CHARLES WARREN LEONARD.
